UNITED STATES PATENT OFFICE.

HARLEY M. CLEARWATER, OF TROY, JOHN TEMPLE, OF WATERVLIET, AND JOSEPH H. RAMSEY, OF ROCHESTER, NEW YORK, ASSIGNEES, BY MESNE ASSIGNMENTS, TO REECE FOLDING MACHINE COMPANY, OF BOSTON, MASSACHUSETTS, A CORPORATION OF MAINE.

BLANK-FOLDING MACHINE FOR THE MANUFACTURE OF COLLARS, CUFFS, AND THE LIKE.

1,149,184.

Specification of Letters Patent.

Patented Aug. 10, 1915.

Original application filed February 11, 1911, Serial No. 608,244. Divided and this application filed June 14, 1912. Serial No. 703,768.

To all whom it may concern:

Be it known that we, HARLEY M. CLEARWATER, a citizen of the United States, residing at Troy, in the county of Rensselaer and State of New York, JOHN TEMPLE, a subject of the King of Great Britain, residing at Watervliet, in the county of Albany and State of New York, and JOSEPH H. RAMSEY, a citizen of the United States, residing at Rochester, in the county of Monroe and State of New York, have invented certain new and useful Improvements in Blank-Folding Machines for the Manufacture of Collars, Cuffs, and the like, of which the following is a specification, reference being had to the drawings accompanying and forming part of the same.

The invention which forms the subject of the present application (a division of our copending application filed February 11, 1911, Ser. No. 608,244, now Patent No. 1,043,722, issued November 5, 1912) relates to machines for turning or folding collar, cuff, shirt-bosom, neckband, wrist-band, and like blanks from which such articles are made, and pertains more particularly to the construction and operation of the fold-defining die or templet commonly used in such machines. In machines of the kind indicated the cloth blank is laid in proper position on a suitable bed or table, after which the templet is seated on the blank. The templet conforms to the finished collar, cuff, or other article, in size and contour, and after it is properly seated the folding blades fold one or more edges of the blank inwardly over the edge or edges of the templet. After this operation (in the machine specifically described in our prior application above mentioned) the templet is collapsed and the folders withdrawn, simultaneously; and as the parts named approach their initial positions a presser is seated on the folded blank edges. Pressure, more or less heavy, is then exerted on the blank edges, by the cooperation of the presser and the bed or table on which the blank rests, to give a sharp and permanent crease to the fold or folds. This crease having been produced the pressure is released and the presser moved away from the folded blank

so that the latter can be removed and an unfolded blank substituted.

As previously stated, the present invention relates particularly to the templet and the operating mechanism therefor; and its chief object is to provide improved devices of simple character which shall be thoroughly effective and reliable in operation.

To this and other ends the invention consists in the novel features of construction and combinations of elements hereinafter described, and more particularly set forth in the appended claims.

Upon reading the subjoined description of the preferred embodiment, in connection with the claims and the accompanying drawings, it will be apparent to those skilled in the art that the invention can be embodied in a considerable variety of forms without departure from its proper spirit and scope. We have therefore not deemed it necessary to refer specifically to any of the numerous modifications and arrangements of which the invention is capable, but have confined our description to the machine which at the present time is believed to exhibit the various features of the invention in their most convenient and effective form.

Referring now to the drawings, Figure 1 is a top plan view of the machine showing the templet and its actuating mechanism, with practically all other parts of the machine omitted. Fig. 2 is a detail cross section, substantially on line 2—2 of Fig. 1, showing also in section the adjustable fulcrum-devices of the lever which contracts and expands the templet. Fig. 3 is a detail plan view of the mechanism for expanding and collapsing the templet. Fig. 4 is a plan view of the head which carries the templet (and also the presser), the view being partly in horizontal section. Fig. 4^a is a detail plan view of part of the above mentioned head.

The above figures correspond respectively to Figs. 3, 4, 6, 7, and 7^a of the drawings in our application Ser. No. 608,244, and the reference numerals used herein refer to similarly numbered parts in said application.

The bed or bed-plate of the machine is

indicated by 20, and is provided with a vertically movable portion or bed 135 actuated by suitable toggles, of one of which a portion is shown at 157. It is upon this 5 movable bed that the blank to be folded is placed.

The movable head 40, carrying the templet, comprises a plate 41, secured by screws 42 on the underside of the forward ends of a 10 pair of arms 43. To permit adjustment of the plate forwardly and rearwardly the apertures in the arms through which the screws pass are in the form of slots 42^a. At their rear ends the head-actuating arms 15 43 are mounted on a rock shaft 44 journaled in brackets 45 extending rearwardly from the back of the bed 20. One of said arms is pinned to the shaft. Extending under the arms and engaging the same by means 20 of adjustable screw stops 46 are two rocker arms 47, 48, the first pinned to the shaft and the second loose thereon and provided with a rearward extension pivotally connected to a downwardly and forwardly extending 25 link, of which a portion is shown at 49. This link is reciprocated by suitable mechanism not shown herein but fully illustrated and described in our copending application before referred to. Suffice it is to say that 30 as the link is reciprocated it rocks the loose arm 48. When the forward end of this arm rises the right-hand arm 43 is raised, and, being pinned to the rock shaft 44, communicates motion to the arm 47, which is also 35 pinned to the shaft. The latter arms in turn raises the left-hand arm 43, which is loose on the shaft. By adjustment of the screw stops 46 the arms 47 and 48 can be made to work in unison, sharing the weight 40 of the head 40 equally. The construction just described obviates the necessity of extremely accurate machine work in making the parts concerned, as will be readily understood.

45 The expandible and collapsible die or templet, designated by 53, is divided longitudinally and transversely into four parts, secured on the bottoms of four carrying plates 54 which are in turn attached to angular 50 actuating members or plates 55 held snugly but movably against the underside of the supporting plate 41 by means of suitable clamping members 56.

The actuating members 55 are themselves 55 actuated through the instrumentality of the pins 57 extending upwardly through arc-shaped slots in the supporting plate 41 into pivotal connection with swinging arms 58, 59, 60, 61, 62, fulcrumed 60 on the said plate. The arms or levers 61 are connected by links 63 to the arms 62. These latter are formed with intermeshing gear segments 64, and the arms 59 are similarly connected by gear segments 65. It will 65 therefore be seen that oscillation of either

lever 62 will give a parallel movement to the connected lever 61, and an equal but opposite movement to the other levers 62 and 61. Similarly, movement of either lever 59 will cause equal and opposite movement of the 70 other lever 59. At the same time the outer and forward pins 57, being guided by their slots and by the arms 58, 60, compel the forward templet segments to move bodily in lines parallel to the forward slots in 75 the supporting plate 41. It will now be seen that suitable actuation of the levers 59 and 62 will cause the templet segments to move inwardly and outwardly along lines parallel to the arc-shaped slots in the supporting plate. To afford wide bearing surfaces for the templet actuating plates 55 the latter are made in sections, as shown in Figs. 4 and 4^a, the alternate sections being connected by vertical plates 55^a to form the 80 respective actuating plates, the sections of each plate extending between those of the other. Thus each plate is supported by both the clamping members or supports 56 when the templet is in its collapsed or contracted 85 position. The templet-carrying members 54 are adjustably attached to the vertical portions, 55^a, of the templet-actuating plates by means of screws 54^a extending through slots 54^b in said carrying members. The 90 same templet can therefore be used for collars of different sizes.

For the purpose of actuating the templet-shifting levers a disk 66 is provided, capable of a partial movement of rotation in either 100 direction about a supporting stud 67 on the supporting plate 41, and connected by a link 68 to the inner end of the left-hand lever 62 and by a link 69 to the left-hand lever 59, said links being connected to the 105 disk on opposite sides thereof. Encircling the disk is a split collar 70, clamped tightly to the disk by means of a screw 71 at the front and having at its rear a notch engaging a roller-stud 72 on the forward end of 110 a lever 73 adjustably fulcrumed at 74 in an arm 75 extending laterally from one of the head-supporting arms 43. At its rear end the lever 73 carries a stud 76 extending into a grove 77 in the rim of a barrel cam 78 115 loose on the rock-shaft 44, so that as the cam revolves the lever will be oscillated, thereby oscillating the disk 66 and shifting the templet segments or sections as before explained. The throw of the lever, and 120 hence the extent of movement of the templet segments, is regulated by shifting the fulcrum block 74 forwardly or rearwardly in the slots 74^a, 74^b, in the arm 75 and lever 73 respectively. The movement of the templet sections can also be regulated by adjustment of the disk 66 in the clamp ring 70. The cam 78 is rotated by a gear 79 fixed to the side of the cam and driven by a gear indicated by the dotted line at 80. The 130

56 latter is driven by suitable mechanism which is fully described in our copending application Ser. No. 608,244, above mentioned, and it is deemed unnecessary to describe the same 5 herein.

57 Of the folders or folder-blades which cooperate with the templet two are shown at 83 and 84^a in Fig. 2. The forward blade, 83, is suitably mounted on a forwardly and 10 rearwardly movable plate 85 mounted on the bed 20, which plate 85 is actuated by convenient and suitable mechanism not herein shown but fully described in our copending application Ser. No. 608,244. It 15 may be said, however, that the timing of the cam 78 and the mechanism which reciprocates the link 49 is preferably such that as the head 40 rises the templet expands and remains expanded until the lowering of 20 the head seats it on the blank which is to be folded. The blank being pressed firmly on the bed by the templet the folders move inwardly, folding the blank-edges over the templet-edges. The bed 135 now drops 25 slightly to relieve the pressure on the templet and the templet then collapses until free of the blank-edges. After the pressing is effected to crease the folded blank edges the head 40 is raised, lifting the templet off 30 the pressed blank. During the latter movement the templet is reexpanded, ready for another folding operation.

35 As previously stated, the invention can be embodied in various devices other than those herein specifically illustrated and described, without departure from its proper spirit and scope as defined by the appended claims.

40 We claim:

1. In a blank-folding machine, in combination, a bed upon which the blank to be folded is placed, an expandable and collapsible templet composed of inwardly and outwardly movable sections, means for seating the templet upon a blank on the bed, and means for expanding and collapsing the templet, comprising actuating members connected with the templet sections, a pivoted disk connected with said members, a clamping collar surrounding the disk, and means associated with the collar to actuate the disk. 45
2. In a blank-folding machine, in combination, a bed upon which the blank to be folded is placed, a head movable toward and from the bed, an expandable and collapsible templet carried by the head and adapted to be seated on the blank on said bed, the templet being composed of inwardly and outwardly movable sections, actuating levers connected to the templet sections, a disk pivotally mounted on the head and connected with said levers to actuate the same and thereby collapse and expand the
3. In a blank-folding machine, in combination, a bed upon which the blank to be folded is placed, a head movable toward and from the bed, an expandable and collapsible templet carried by the head and composed of inwardly and outwardly movable sections, actuating members connected with the templet sections and geared together whereby to cause said sections to move simultaneously, and means for actuating the geared members. 55
4. In a blank-folding machine, in combination, a bed upon which the blank to be folded is placed, a forwardly extending supporting arm pivoted in rear of the bed, a head mounted on the supporting arm, means for actuating the supporting arm to move the head toward and from the bed, an expandable and collapsible templet carried by the head and composed of inwardly and outwardly movable sections, a lever carried by the arm, means for actuating the lever, and mechanism connecting the lever and the templet to expand and collapse the latter, said mechanism including a rotatively adjustable element to regulate the extent of movement of the templet sections. 60
5. In a blank-folding machine, in combination, a bed upon which the blank to be folded is placed, a supporting arm pivotally mounted in rear of the bed and extending forwardly over the same, a head carried by the arm, means for actuating the arm to raise and lower the head, an expandable and collapsible templet carried by the head and composed of inwardly and outwardly movable sections, a forwardly and rearwardly extending lever carried by the arm, a cam engaging the rear end of the lever to oscillate the same, and mechanism connecting the forward end of the lever with the templet to expand and collapse the same, said mechanism including a rotatively adjustable element to regulate the extent of movement of the templet sections. 65
6. In a blank-folding machine, in combination, a pivotally mounted supporting arm, a head carried thereby, a pivoted disk mounted on the head, a lever carried by the arm and having an adjustable fulcrum, means connecting the lever with the disk to actuate the latter, and an expandable and collapsible templet carried by the head and connected with said disk for actuation thereby. 70
7. In a blank-folding machine, in combination, a head having a supporting plate, a movable angle plates mounted on said plate, an expandable and collapsible templet composed of inwardly and outwardly movable

sections connected to the depending portions of said angle plates, actuating levers mounted on the supporting plate and connected with the angle plates, a pivotal disk mounted on the supporting plate and connected with the said levers to actuate the same, movable supporting means for the head, and a lever carried by said means and connected with the said disk to actuate the same.

10 8. In a blank-folding machine, in combination, a head, an expansible and collapsible templet carried by the head and composed of inwardly and outwardly shiftable sections, a disk pivotally mounted on the head and connected to the templet sections to shift the same, an adjustable clamping ring on the disk, and a lever connected to the ring, to actuate the disk.

9. In a blank-folding machine, in combination, a head, a templet carried by the head and composed of inwardly and outwardly shiftable sections, oscillatory means carried by the head and connected to the templet sections to shift the same, a lever connected with the oscillatory member to actuate the same, and a fulcrum for the lever adjustable longitudinally thereof to vary the extent of movement of the oscillatory member.

10. In a blank-folding machine, in combination, a movable head, an arm connected to the head to move the same, a templet carried by the head and composed of inwardly and outwardly shiftable sections, an oscillatory member carried by the head and connected to the templet sections to shift the same, a lever supported by the arm and connected to the oscillatory member to actuate the same, and means for actuating the lever.

11. In a blank folding machine, in combination, a movable templet head, a pivoted arm connected to said head for swingingly moving the same, a templet carried by the head and comprising inwardly and outwardly shiftable sections, a to and fro shiftable templet operating lever supported by said arm, means connecting said lever with said templet sections whereby the lever movements effect section movements, said connecting means including a pivoted element from which the sections take their movement and adjustable to regulate the movement of the sections as effected by the movement of the lever, and a circularly moving cam concentric with the pivot of said arm for actuating said lever.

12. In a blank-folding machine, in combination, a bed upon which the blank to be folded is placed, a rock shaft supported by the bed, a relatively long arm rigidly mounted on the shaft and extending over the bed, a short arm loosely mounted on the shaft and adjustably connected with the said long arm, means for actuating the short arm to rock the long arm and the shaft, a

second long arm loosely mounted on the shaft and extending over the bed, a short arm rigidly mounted on the shaft and adjustably connected to the last named long arm to rock the same as the shaft is rocked, a head carried by the long arms and movable therewith toward and from the table, and a fold-defining templet carried by the head.

13. In a blank-folding machine, in combination, a vertically movable bed on which the blank to be folded is placed, a head movable toward and from the bed, an expansible and collapsible templet carried by the head and adapted to be seated on the blank, and means for collapsing the templet while seated on the blank, the bed moving slightly downward prior to the collapse of the templet.

14. In a blank-folding machine, in combination, a head comprising a supporting plate, shiftable members slidably carried by said plate and provided with depending portions, templet sections carried by the depending portions, two pairs of geared levers mounted on said plate, connected to said shiftable members to shift the same, and means for actuating one lever of each pair.

15. In a blank-folding machine, in combination, a head comprising a supporting plate, shiftable members slidably carried by the plate and provided with depending portions, levers mounted on the plate, connected with the shiftable members to actuate the same and having intermeshing gear-teeth whereby one lever may actuate the other, means to actuate one of the levers, and templet sections carried by the depending portions of the shiftable members.

16. In a blank-folding machine, in combination, a head having a supporting plate, movable templet-sections depending from the plate, a pair of levers pivoted on the plate on spaced apart pivots and having inwardly extending intermeshing toothed portions, said levers being connected with a pair of templet-sections to actuate the latter, a second pair of pivoted levers similarly geared together and connected with another pair of templet-sections, and actuating means arranged between the two pairs of levers and connected to one lever of each pair.

17. In a blank-folding machine, in combination, a movable head having an elongated supporting plate, a pair of levers pivoted to the plate on spaced apart pivots near the rear edge having toothed-portions extending into mesh with each other, a similar pair of levers similarly connected together and mounted on the plate at its forward edge, an actuating member pivoted to the plate at its center, links connecting the actuating member to one lever of each pair, means to oscillate the actuating member on its pivot,

and inwardly and outwardly movable templet-sections connected one to each lever for actuation thereby.

18. In a blank-folding machine, in combination, a supporting plate, shiftable templet-sections depending from the plate, levers pivoted on the plate and connected with the templet-sections to actuate the same, a disk pivoted on the plate and connected with 10 the levers to actuate the latter, a split ring encircling the disk, said ring having means for binding it tightly to the disk and having a notch at one side, a lever having a stud extending into said notch, and means for 15 oscillating the lever.
